CLAIM

The ornamental design for a vacuum fixation device, as shown and described.

DESCRIPTION

FIG. 1 is a top perspective view of the vacuum fixation device showing my new design;

FIG. 2 is a right side perspective view thereof;

FIG. 3 is a rear and bottom perspective view thereof;

FIG. 4 is a front elevational view thereof;

FIG. 6 is a top plan view thereof;

FIG. 7 is a rear elevational view thereof;

FIG. 8 is a right side elevational view thereof; and,

FIG. 9 is a bottom plan view thereof.

FIG. 1

FIG. 2**FIG. 3****FIG. 4****FIG. 5****FIG. 6****FIG. 7****FIG. 8****FIG. 9**UNITED STATES PATENT AND TRADEMARK OFFICE
CERTIFICATE OF CORRECTION

PATENT NO. : Des. 348,133

DATED : June 21, 1994

INVENTOR(S) : Poul Solfjeld

It is certified that error appears in the above-identified patent and that said Letters Patent is hereby corrected as shown below:

On the title page, under "DESCRIPTION", after "FIG. 4, please add
--FIG. 5 is a left side elevational view thereof;--

Signed and Sealed this

Fourth Day of October, 1994

Attest:

BRUCE LEHMAN

Attesting Officer

Commissioner of Patents and Trademarks
